UNITED STATES PATENT OFFICE

162,148

FILM STRIP VIEWER

Robert B. Fuller, Burbank, Calif., assignor to
Craftsmen's Guild, Hollywood, Calif., a partnership

Application May 31, 1949, Serial No. 2,964

Term of patent 3½ years

(Cl. D61—1)

To all whom it may concern:

Be it known that I, Robert B. Fuller, a citizen of the United States and a resident of Burbank, California, have invented a new, original, and ornamental Design for a Film Strip Viewer, of which the following is a specification, reference being had to the accompanying drawing, forming part thereof.

Referring to the drawing:

Fig. 1 is a perspective view of a film strip viewer, showing my new design;
Fig. 2 is a front elevational view;
Fig. 3 is a side elevational view;
Fig. 4 is a rear elevational view; and
Fig. 5 is an elevational view of the opposite side as shown in Figure 3.

I claim:

The ornamental design for a film strip viewer, as shown.

ROBERT B. FULLER.
